UNITED STATES PATENT OFFICE.

WILLIAM WATTIE, OF WORCESTER, MASSACHUSETTS, ASSIGNOR TO THE KNOWLES LOOM WORKS, OF SAME PLACE.

WIRE-LIFT NEEDLE FOR JACQUARD MACHINES.

SPECIFICATION forming part of Letters Patent No. 394,800, dated December 18, 1888.

Application filed June 2, 1888. Serial No. 275,887. (No model.)

To all whom it may concern:

Be it known that I, WILLIAM WATTIE, a citizen of the United States, residing at Worcester, in the county of Worcester and State of Massachusetts, have invented certain new and useful Improvements in Wire-Lift Needles for Jacquard Machines; and I do hereby declare that the following is a full, clear, and exact description thereof, which, in connection with the drawings; making a part of this specification, will enable others skilled in the art to which my invention belongs to make and use the same.

My invention relates to wire-lift needles for Jacquard machines in which the top of the needle is bent over to form a hook to work in conjunction with the lift-plate or griff, and the bottom of the needle is bent backward upon itself, forming a **U**, which serves to guide the needle in a slot in a guide-plate, the end of the back part being bent into a hook, which works in conjunction with a lift-bar on the guide-plate.

The object of my invention is to tie together and confine in a cheap and effective manner the parts of the **U** of the needle, so as to prevent the needle from being turned out of its proper position in the guide-slot, and the machine being thereby deranged.

Referring to the drawings, Figure 1 represents a wire-lift needle of my improved construction, with a detached section of the guide-plate. Fig. 2 is a plan of one of the confining-bands which tie the two parts of the **U** together. Fig. 3 represents the band shown in Fig. 2 after it is set or compressed upon the **U** part of the needle; and Fig. 4 is a plan of a detached portion of the guide-plate, showing the ordinary construction of the wire-lift needles, with one in its proper position and one turned out of position, as will be herein-after fully described.

In the accompanying drawings, 1 is the principal wire of the needle, and 2 the part bent back upon itself. 3 is the confining-band, which ties the two parts together. 4 is the top hook, and 5 the griff with which it works. 6 is the lower hook; 7, the lift-bar on the guide-plate 8, and 9 is the slot in the guide-plate.

The lift-needles are placed in the Jacquard

machine in rows as near together as they can be worked, and the cords connecting them to the loom-harnesses or other mechanism which it is desired to work by the jacquard are attached at the lower end, 10.

The mechanism by which the griffs 5 and the guide-plates 8 are reciprocated, and the indicator-needles which effect the engagement and rise of hook 4 with griff 5, or the missing 60 of griff 5 by hook 4 and the descent of the needle with the plate 8, form no part of my invention and are not shown, and the same may be arranged in various ways, as will readily be understood by those familiar with wire- 65 lift Jacquard machines.

If in practice the cords could be made always to pull directly down from the center of the bend 10, the trouble which my improved needle is intended to obviate would not occur; 70 but it frequently happens that the cords pull in such a way as to spring the two parts of the **U** of the needle toward each other near hook 6 and allow the needle to spring into the position shown at 11, Fig. 4, the proper 75 position being shown at 12, same figure.

When in the position 11, the needle cannot work properly, and the hook 6 may become entangled with its neighbor. It often happens that the needles are in this way bent out 80 of shape, necessitating the stoppage of the machine till they can be replaced.

When the band 3 is in place and compressed upon the **U** part of the needle, the needle cannot turn in its slot 9, and the hooks 4 and 6 85 must always be in proper position for engagement with the lift plates or bars. The band 3 may be more firmly secured on the needle 1 by means of soft soldering, if desired.

It will be observed that the part of the hook 90 6 adjoining the band 3 is bent outward, so that when the hook rests upon the bar 7 there is a space between the band 3 and the side of the bar 7, and also that the slot 9 is so placed in the guide-plate 8 with reference to the bar 7 95 as to keep the band 3 from touching the bar when the needle slides past it. The object of this construction is to prevent the band 3 from touching the bar, for if it was allowed to come in contact with it, it would soon wear 100 through the light band and destroy the tie.

Having thus described my invention, what

I claim as new, and desire to secure by Letters Patent, is—

1. The combination, with a wire-lift needle having the double **U** portion at its lower part, of a band applied thereto, substantially as set forth.

2. The combination, with a wire-lift needle, and a band applied to the double portion

thereof, of the lift-bar, and the guide-plate having a slot, 9, therein, for the purpose 10 stated, substantially as shown and described.

WILLIAM WATTIE.
